FIG. 6.

UNITED STATES PATENT OFFICE.

ANTHONY GERSTENKORN, OF BROOKLYN, NEW YORK.

MACHINE FOR PREPARING ROLLED BEEF.

Application filed February 13, 1928. Serial No. 253,864.

This invention relates to machines for preparing rolled beef preliminary to the usual smoking process.

At the present time the rolled beef is prepared by manual operation, the beef first being wound by a workingman tightly around a needle or pin, the loose end of the same sewed to the body of it, after which a cord is tightly wound in a helical formation around the roll and fastened and finally a loop is made at the one end of the same whereby it may be hung on appropriate hooks in the smoking chambers.

It is obvious that this manual process involves many complicated slow operations, requiring exceptional skill on the part of the workingman, so that it is inefficient and expensive.

The main object of my invention is to replace said manual operations by mechanical processes and particularly to provide one single machine which will be adapted to execute in a convenient manner all the herein described operations.

Another object of this invention is to provide a machine of the mentioned character which will execute said operations in a quicker, cheaper and more perfect manner than has been done by hand labor.

Still another object of my invention is to provide a machine for executing all the mentioned operations which will be adapted to be manipulated by one single workman.

Features of the invention are to be found in a rotatably arranged horizontal shaft having an arm hinged thereon adapted to be opened or to be closed thereon and to rotate therewith. The beef will be clamped between the shaft and the hinged arm and mechanical means are provided to rotate the shaft, while other automatic means will roll up and increasingly compress the beef around the shaft. A hinged link mechanism arranged in parallelism to the shaft may now be brought into operation, a member of the same having a plurality of needles in a transversal direction to the shaft so that the sewing of the roll along its length may be executed with one single operation. The link mechanism being again thrown out of operation a cord may be guided by a longitudinal screw around the rolled beef in a helical formation and tightly wound thereon,

afterwards the ready roll may be slipped off from around and between the shaft and the hinged arm.

In order that its construction and operation may be readily comprehended, I will now proceed with a full clear and specific description of the invention, having reference to the accompanying drawings, which show an approved embodiment thereof, and in which:

Fig. 1 is a front view of my machine;

Fig. 2 is an end view of it, parts of the same being broken away and the link mechanism carrying the sewing needles being thrown out of operation in both Figures.

Fig. 3 is a partly sectional side elevation of my machine showing both the sewing needles and the beef compressing mechanism in operative positions.

Fig. 4 is a partly sectional plan view of my device illustrating the sewing operation.

Fig. 5 is a semi diagrammatical detail showing the execution of the sewing operation.

Fig. 6 is a view of a ready roll illustrating the sewing and the tightly wound cord thereon.

Figs. 7 and 8 show details of the cord guiding mechanism, while

Fig. 9 indicates a modification in the cross section of my rotating shaft and the hinged arm thereon.

Like characters of reference mark the same parts wherever they occur in the drawings.

Referring now to the drawings by characters of reference, the numeral 10 indicates the supporting frame structure of my machine, having a table 11 thereon. Three bearings 12 are arranged on the table rotatably carrying the shaft 13 which may be driven by an electric motor 14 through a chain 15 and sprocket wheel 16 or by hand through a crank 17.

The shaft 13 has a universal joint 18 (of any of the usual constructions) inserted therein permitting the left hand end of said shaft to be lifted out of line from its stationary right hand portion in any desired direction when the left hand end 19 of the shaft is lifted out of the respective bearing 12^a. For this purpose a cover 12^b of the bearing is made hinged and is normally secured by a hinged bolt and wing nut 20 which may be loosened and thrown out of engagement when the cover 12^b may be thrown into the position in

dicated by the dot and dash lines as at 12°. The construction of this portion of my machine is not shown in fuller detail since it is a well known standard element in machine building and will be obvious from Fig. 1.

The left hand hinged portion 13^a of the shaft is made substantially with a semi-circular cross section and the arm 21 may be secured hinged thereto leaving an appropriate space 22 therebetween for a major part of their length but closing on the end portion 19 of the shaft for a desired distance, completing the cross section of the two into a full circle so as to permit them to rotate in bearing 12^a.
 15 An upstanding and backwardly extended upper frame structure 23 is secured to the rear of the table carrying the linked frame indicated in general by the numeral 24 and consisting of two supporting link members 25 hinged in the two rear-most upstanding frame members 23^a, as at 26, kept thereon with yielding pressure by the spring 27, the two front link members 28, hinged at the upper ends of members 25, as at 29, and also 25 hingedly connected at their lower end to a cross bar or shaft 30, as at 31. The cross bar 30 carries two depending arms 32 slidable thereon, the lower ends of arms 32 being secured to a cross bar 33 carrying a plurality of sewing needles 34 arranged in parallelism. A handle 35 is also arranged on the front of the needle carrying bar 33. The whole link frame structure may be thrown out of operating position, as in Fig. 2, or brought down 35 into the operative position, as indicated in Fig. 3. A vertically slidably shaft 36 is further arranged in about the center line of the machine underneath the table 11, being guided in a vertical bearing at 37 arranged in a member 38 supported by the table 11 and portions of the frame structure 10. A sleeve or collar 39 is secured to the shaft 36 whereby its downward movement is limited, said sleeve 39 resting on the member 38. The upper end 40 of the shaft 36 carries a curved frame structure 40 with a basket like curved chain structure 41 arranged thereacross. The supporting frame 40 consists of two end members 40^a and three longitudinal members 40^b secured to each other as shown. Braces 40^c are secured to the ends of the middle longitudinal member 40^b and to the collar 39 to further secure the curved frame 40 on the top of the shaft 36. Chains 41^a are secured at their ends in the respective upper and longitudinal members 40^b in parallelism with one another and in a somewhat slack condition so as to take the curve shown in Fig. 2 and thereby form a somewhat loose yielding curved basket like structure 41 underneath and along the shaft portion 13^a. The lower end 36^a of the shaft 36 rests on a pedal structure 42 and the shaft and its frame 40 are of such weight, that normally the whole structure will take up the position indicated in

Fig. 2 while it may be gradually raised by a pressure exerted on the pedal plate 42^a, as indicated in Fig. 3.

A cross bar 43 may be provided secured to the lower upstanding members 23^b of the rear frame structure 23 at the center of which a yielding frame 44 is provided swingable around a pin 45 in the socket member 46. The right hand vertical member 47 of the frame 44 is slidably arranged in a horizontal bottom member 48 so that it may be adjusted in positions nearer to or farther away from the left hand stationary vertical member 49 for which purpose a handle 50 is provided thereon. A bore is provided at the bottom of the movable frame member 47 and corresponding bores 51 in the branch 48 may be brought into registering relation with the bore in the member 47 and said member secured in its adjusted position by a pin 52 which may be arranged at the end of a chain 53. Opposingly set pins 54 are provided on the members 47 and 49 and a roller or spool 55 may be arranged on the pins 54, said roller being adapted to receive a comparatively heavy and strong cord 56 (Fig. 2) to be used in tying the rolled and sewed beef tightly together. Springs 57 are provided yieldably securing the spool 55 in its central position.

To guide the cord 56 a member 58 is provided, made slidable along a transverse shaft 59 arranged between the two lower vertical members 23^b, and moved by a screw 60 journaled in bearings 61 in the lower part of said members 23^b, underneath the shaft or rod 59 (Figs. 2 and 7).

The guide 58 consists of sliding hub 62 engaging the shaft 59 by a key and groove arrangement and an arm 63 swingable as at 63^a and having a half nut 64 at its end. The nut normally engages the threads on screw 60 under the influence of spring 65 and is moved by the screw when the same is rotated, but may be thrown out of engagement, as indicated by the arrow 66, and thrown entirely around and over shaft 59 passing a dead point and then being secured in this upper inoperative resting position by the same spring 65, as will be understood.

The nut 64 carries an upstanding arm 67 which has a relatively stationary jaw 68 and a movable jaw 69 at its upper end (Fig. 8). The movable jaw 69 is guided on screw bolts 70 having nuts 71 thereon and spring 72 interposed between the nuts and the jaw 69 so as to press the same against the stationary jaw 68 by adjustable pressure. The cord, or rope 56, is lead through between the two jaws and will have to overcome an adjusted amount of friction and kept as taut as desired for the operations to be described hereinafter. A catch or handle 73 may be provided for manipulating the movable jaw 69 while the half nut 64 may be swung into or out of engagement by using the arm 67 itself as its handle.

For the driving of the screw 60 a chain drive 74 may be provided between it and the shaft 13 (Fig. 4) with the respective sprocket wheels 75 and 76. By exchanging one or both of the sprocket wheels, the screw 60 may be driven faster or slower in relation to shaft 13 and the cord 56 tied in closer or further windings around the rolled beef, as will be described presently.

10 On the left hand side of the table 11 a stand 77 may be conveniently arranged carrying the spools 78 with the thinner sewing cord 79 thereon, ready to be used.

The operation and use of my machine may 15 now be described as follows:

A usual flat piece of beef 80 (Fig. 3) will be caught between shaft portion 13^a and hinged arm 21 in the space 22 which is made gradually reduced towards the left hand 20 meeting ends of the two, as somewhat exaggeratedly shown in Fig. 1, so as to accommodate various thicknesses of beef. The shaft 13 is then set in motion and the frame 40 and basket 41 gradually raised by the use 25 of the pedal 42 and rising through the opening 11^a in the table 11. This will cause the beef to be wound or rolled around the shaft 13 and to be compressed to a desired degree, as indicated in Fig. 3.

30 After the beef is rolled and compressed, temporary hooks 81 may be driven thereinto to hold the end 80^a of the same to the body thereof while the sewing operation is being performed.

35 Instead of the hooks 81 other means may be used for the purpose, so, for instance, releasable means may be provided to lock the frame 40 in its uppermost position and so to hold the rolled beef.

40 The link frame 24 is now brought down from its inoperative and out of the way position shown in Figs. 1 and 2, into that indicated in Fig. 3 by making use of the handle 35. The bar 33 may now be slid into position, 45 if needed with its needles 34 on shaft 30 and the needles thrust through the beef, as indicated in Fig. 4. While these operations are taking place, the link mechanism 24 may be supported by a toothed arm 82, rockable on 50 shaft 59 and engaging in one of the spaces between its teeth the pin 83 on the link frame 24. Its service performed, the arm 82 may be thrown back resting on a portion 84 of the rear frame 23, as in Figs. 1 and 2.

55 For the sewing operation the thinner and lighter but strong and resisting cord or thread 79 is now drawn from the spool 78 and across the hooks 34^a in needles 34 whereupon the needles are withdrawn, as indicated 60 in Fig. 5, producing the loops 85 across the rolled beef 86.

A hand tool or needle 87 is taken now, another piece of cord or thread 88 inserted into its hook or eye 87^a and drawn across all the 65 loops 85, as indicated by the arrow 87^b in Fig.

5 The necessary portion of the cord 79 is now severed from the rest on its spool and drawn tight at its two ends 79^a and 79^b thereby by drawing the loops 85 tightly on the roll of beef. The respective ends of cords or threads 70 79 and 88 are not tied together and the roll of beef is sewed as indicated at 89 in Fig. 6.

The heavier cord 56 has been kept in rest up to now its guide 58 being preferably at the left hand end of screw shaft 60 where it is 75 of reduced circular cross section without threads.

To prepare the tight windings 90 of Fig. 6 around the sewed rolled beef, the frame 40 is permitted to drop back into its low position 80 or hooks 81 removed from the beef roll, the end of cord 56 tied tightly around the left end of the sewed roll and the shaft 13 and screw 60 set in motion after the half screw 64 of guide 58 is inserted into the screw threads 85 about opposite to the left hand end of the beef roll. The rotating roll will pull rope or cord 56 against the adjusted friction in guide 58 and the moving of guide 58 along screw 60 and the rotation of shaft 13 will produce a 90 tight helical rope winding around the roll of beef. When the whole length of the roll is wound with a number of helical turns depending on and regulated by the relative speeds of shafts 13 and 60, the farther end of cord 56 may be tied tightly to the last turn of it, as at 91, and a remaining end of the same formed into the loop 92 crossing to the other side of the beef roll 86, whereby to hang it up in the smoking chambers. 100

All the operations necessary to prepare the roll for smoking have thus been finished on my single machine and in order to remove the ready roll therefrom, the cover of bearing 12^a is thrown open, shaft portion 13^a lifted 105 with the rolled beef thereon and the roll slipped off from the same.

Instead of the cord 56, I may use lengths of wire, or chains in a similar manner to wind around the roll and these may be used over 110 and over again, thereby effecting further and considerable saving.

The cooperating shaft portion 13^a and hinged arm 59 may have the cross section indicated in Fig. 9 so as to better grip the beef end introduced between them, by the action of longitudinal groove 93 and key 94. 115

Changes and variations may be made in the construction of the parts within the limits of the claims without departing from the spirit 120 and scope of the invention.

As one of such changes, I particularly want to remark that the whole guide 58 may be omitted as well as the drive to screw shaft 60, rope 56 wound around one or two turns of the screw 60 and the helical winding of rope 56 around the beef roll accomplished by letting the rope itself rotate shaft 60, its winding in the screw threads automatically providing for the taut condition of the rope and 125 130

for the distribution of helical turns on the beef roll.

What I claim as new, is:

1. In a machine for preparing rolled beef, 5 in combination, means to roll the piece of beef around a central element, means to tighten said roll around said central element, means to sew the free end of the roll to its body and means to wind a cord tightly around said roll.
- 10 2. In a machine for preparing rolled beef as set forth in claim 1, said means to roll a piece of beef around a central element consisting of a rotatable shaft, an arm hinged at the one end of the same on said shaft and adapted 15 to clinch the end of the beef between the two.
- 15 3. In a machine for preparing rolled beef as set forth in claim 1, said means to tighten the roll around said central element consisting of a substantially semi-cylindrical member 20 underneath and in line with the roll to be produced, being normally in a lowered position, but adapted to be gradually raised and engage a roll of beef.
- 25 4. In a machine for preparing rolled beef as set forth in claim 1, said means to tighten the roll of beef around its central element consisting in a substantially semi-cylindrical basket structure composed of a frame and slack chains thereacross, a slideable vertical 30 shaft for the frame, means to normally keep said basket structure in a lowered position and a pedal adapted to yieldably and gradually raise said basket structure and engage the beef.
- 35 5. In a machine for preparing rolled beef as set forth in claim 1, said means to sew the roll of beef including a plurality of needles secured in parallelism with one another in a frame adapted to simultaneously pierce the 40 beef roll therewith, said needles having hooked ends whereby to withdraw a plurality of cord loops through the body of the beef to form stitches therethrough.
- 45 6. In a machine for preparing rolled beef as set forth in claim 1, said means to sew the beef roll including a hinged link structure; a plurality of needles having hooked ends attached thereto, said structure being adapted 50 to throw said needles in line with the beef roll, or out of line therefrom.
- 55 7. In a machine for preparing rolled beef as set forth in claim 1, said means to tightly wind a cord around the beef roll including a source of cord and a rotatable screw shaft in parallelism with the beef roll and adapted to 60 guide a cord in helical formation around the beef roll.
- 60 8. In a machine for preparing rolled beef as set forth in claim 1, said means to wind a cord around a beef roll including a source of

cord; a guide means for the cord adapted to exert adjustable frictional resistance to the passing of the cord therethrough; a shaft in parallelism with the beef roll, and cooperating elements on the shaft and guide means to lead said guide along the shaft.

9. In a machine for preparing rolled beef as set forth in claim 1, said means to wind a cord around a beef roll including a source of cord; a guide means for the cord adapted to 70 exert adjustable frictional resistance to the passing of the cord therethrough; a shaft in parallelism with the beef roll, and cooperating elements on the shaft and guide means to lead said guide along the shaft, said cooperating 75 means comprising screw threads provided both on the shaft and guide means.

10. In a device for preparing rolled beef, means to roll a piece of beef around a central element consisting of a rotatable shaft, an 80 arm hinged at the one end of the same on said shaft and adapted to clinch the end of the beef between the two.

11. In a device for preparing rolled beef, 85 means to tighten the roll around a central element consisting of a substantially semi-cylindrical member underneath and in line with the roll to be produced, being normally in a lowered position, but adapted to be gradually raised and engage a roll of beef.

12. In a device for preparing rolled beef, 95 means to tighten the roll of beef around its central element consisting in a substantially semi-cylindrical basket structure composed of a frame and slack chains there-across, a slideable vertical shaft for the same, means to normally keep said basket structure in a lowered position, and a pedal adapted to yieldably and gradually raise said basket structure and engage the beef therewith.

13. In a device for preparing rolled beef, means to sew the roll of beef including a plurality of needles secured in parallelism with one another in a frame adapted to simultaneously pierce the beef roll therewith, said 100 needles having hooked ends whereby to withdraw a plurality of cord loops through the body of the beef to form stitches therethrough.

14. In a device for preparing rolled beef, means to sew the beef roll including a hinged link structure; a plurality of needles having hooked ends attached thereto, said structure being adapted to throw said needles in line with the beef roll, or out of line therefrom.

Signed at New York, in the county of New York, and State of New York, this 9th day of February, A. D. 1928.

ANTHONY GERSTENKORN.
